UNITED STATES PATENT OFFICE.

EPIFANIO V. N. TOMASULO, NOW BY JUDICIAL CHANGE OF NAME NESTOR NICHOLAS
TOMASULO, OF PHILADELPHIA, PENNSYLVANIA.

POWER HAIR CLIPPER.

Application filed January 6, 1922, Serial No. 527,454. Renewed May 5, 1924.

To all whom it may concern:

Be it known that EPIFANIO V. N. TOMASULO, a subject of the King of Italy, residing at Philadelphia, in the county of Philadelphia and State of Pennsylvania, has invented certain new and useful Improvements in Power Hair Clippers, of which the following is a specification.

This invention relates to improvements in hair clippers, and more particularly to that type of clipper which is automatically operated by a small electric motor.

An object of the invention is to provide a suitable automatic hair clipper which will be provided with a small electric motor for operating the cutter plate, and also provided with a fan or blower to keep the hair that is cut from clogging up between the fixed cutter plate and the oscillating cutter plate.

A further object of the invention is to provide an automatic hair cutter which will be electrically driven, and will be provided with clutch mechanisms to selectively operate the cutter plate at either end of the clipper.

A still further object of the invention is to provide a suitable double hair clipper, which will be positive in operation, and inexpensive to manufacture.

Other objects will appear as the description proceeds.

In the accompanying drawings which constitute a part of my application,

Figure 1 is a plan view of my improved hair clipper with the cover plate removed;

Figure 2 is a longitudinal sectional view of the hair clipper with cover plate in position;

Figure 3 is a sectional view taken on the line 3—3 of Figure 2;

Figure 4 is a sectional view taken on the line 4—4 of Figure 2;

Figure 5 is a sectional view taken on the line 5—5 of Figure 2;

Figure 6 is a sectional view taken on the line 6—6 of Figure 2, and

Figure 7 is a detail view of the cam and end of yoke on the lever connecting the cutter plate.

Like characters of reference will be used throughout the following specification to designate corresponding parts.

The clipper body 1 is approximately rectangular in cross section, and is provided with the spaced webs or partitions 2 which are formed integral therewith.

Positioned between the web portions 2 is a small electric motor 3, which is attached to the bottom of the casing at 4. The motor shaft 5 extends out beyond the ends of the motor and through the partitions 2, and have attached at their outer ends the toothed clutch heads 6 and 7. Pivoted to the ears 8 on the casing 1, are the bell crank lever yokes 9, which carry the oppositely disposed pins 10, which are free to move in the slots 11 formed around the clutch heads 6 and 7. The operating push buttons 12 are pivoted to the free ends of the bell crank levers 9, and extend through the side walls of the casing 1. Springs 13 connect the bell crank levers with the web partitions 2, to normally hold the clutch members in disengagement.

A small fan or blower 14 is attached to the shaft 5 adjacent the motor 3, and acts to cool the motor when the clipper is in use, and also serves to keep the cutter plates clean from hair. The shaft 5 is passed through the bushings 15 in the partitions 2 and acts as bearings therefor.

Positioned between the partitions 2 and the ends of the clipper, are the standards 16, in which are mounted the shafts 17. Fixed to the inner ends of these shafts 17, are the clutch heads 18, which are adapted to be engaged by the clutch heads 6 and 7, it being readily seen and understood that only one set of clutch members may be engaged at a time. The opposite ends of the shafts 17 carry the cam members 19.

The tensioning caps 20, are provided with a thickened central portion 21, through which extends the vertical posts 22. These posts 22 are screw threaded at their opposite ends, and extend through the tension caps 20 and also the oscillating cutter bars 23. Springs 24 are placed over the upper ends of posts 22, which tension the several parts, and hold them in their adjusted position. Nuts 25 screw down on to the springs 24, and keep them in position.

It will be noticed that the tension caps 20 are provided with upwardly curved

flange portions 26, which seat on or engage the walls of the casing 1.

The opposite ends of the casing 1, are provided with the downwardly extending 5 curved portions 27, which extend at their outer or free ends in an upwardly and angular manner, with respect to the casing proper. The usual form of fixed cutter plate 28, is attached to the ends of the 10 casing, and extends in the same plane as does the free ends 29 of the casing 1. The movable cutter plates 30 are positioned on top of the fixed cutter plates 28, and have attached thereto the outer ends of the oscillating cutter bars 23. The cutter bars 23 are pivoted at their centers to the vertical tension posts 22, and have their inner ends formed into yokes 31, which are engaged by the cams 19, in such a manner that 15 an oscillating motion may be transmitted to the said bars.

The oppositely disposed knobs 32 are formed at the top of the casing walls, and are provided internally screw threaded 25 sockets 33, to receive the screws which hold the cover plate 34 in position on the casing 1. The cover plate 34 is further provided with the spaced partitions 35, which abut against the partitions 2, thereby reinforcing the said casing.

It will be understood that many minor changes in detail of construction may be resorted to without departure from the spirit of the invention.

35 I claim:

1. A power hair clipper comprising a hollow casing, angularly disposed cutter plates attached to the opposite ends of said casing, a motor positioned in said casing, and clutch 40 mechanisms for selectively operating either end of said clipper.

2. A power hair clipper comprising a casing, angularly disposed cutter plates attached to the opposite ends of said casing, 45 bracing means formed in said casing, a motor positioned in said casing, and clutch mechanisms for selectively operating either end of the clipper.

3. A power hair clipper comprising a rectangular casing, spaced bracing webs formed integral with said casing, a motor mounted between said webs, a fan adjacent said motor, cutter plates positioned at the opposite ends of said casing, clutch mechanisms for selectively driving either cutter, and a cover plate detachably secured to the top of said casing.

4. A power hair clipper comprising an elongated casing, clipper elements at the ends 60 of said casing, a motor mounted in said casing, clutch mechanisms between said motor and said clipper elements, and means carried by said casing for selectively driving either of the clipper elements.

65 5. A power hair clipper comprising a cas-

ing, clipper elements at the ends of said casing, a motor mounted in said casing, an elongated shaft extending through said motor, clutch heads carried on the ends of said shaft, spaced standards positioned at the 70 opposite ends of said motor, shafts mounted in said standards, clutch heads carried on the inner ends of said shafts, and means for operating the clipper elements carried by the outer ends of said shafts.

6. A power hair clipper comprising a casing, downwardly extending curved portions formed at the ends of said casing, clipper elements at the ends of said casing, a motor, 80 means connecting said motor with said clipper elements, a fan in said casing operable by said motor, said fan being adapted to circulate air through said casing and over the movable parts therein for preventing heating thereof.

7. A power hair clipper comprising a casing, downwardly extending curved portions formed at the ends of said casing, clipper elements formed on the free ends of said curved portions, a motor in said casing, 90 clutch mechanisms connecting said motor with said clipper elements, and a fan operable by said motor, the air from said fan circulating through said casing in such a manner as to follow the contour thereof.

8. A power hair clipper comprising a casing, angularly disposed clipper elements at the ends of said casing, a motor, clutch mechanisms positioned between said motor and clipper elements, means for operating said mechanisms, adjustable tension caps for said clipper elements, and a cover plate for said casing, substantially as described.

9. A power hair clipper comprising a casing, angularly disposed clipper elements at 105 the ends of said casing, a driving motor in said casing, means for selectively operating either clipper element or both at the same time, and means for cooling the working parts.

10. A power hair clipper comprising a casing, spaced partitions in said casing, a motor, clipper elements at the ends of said casing, means connecting said elements and motor, a cover plate for said casing, spaced partitions in said plate adapted to engage and coat with said partitions in said casing, whereby added strength will be afforded the casing.

11. A power hair clipper comprising a 120 casing, cooperating clipper elements supported on each end of the casing, bearings within the casing supporting a plurality of rotatable shafts, means for converting the rotary motion of the shafts into vibratory motion of the movable clipper elements, propelling means including mechanism whereby any of the said shafts may be selectively engaged and rotated.

12. A power hair clipper comprising a 130

casing, cooperating clipper elements supported on each end of the casing, bearings within the casing supporting a plurality of rotatable shafts in longitudinal alinement, means for converting the rotary motion of the shafts into reciprocatory motion of the movable clipper elements, propelling means

including mechanism whereby any of the said shafts may be selectively engaged and rotated.

In testimony whereof I affix my signature.

EPIFANIO V. N. TOMASULO.
